UNITED STATES PATENT OFFICE.

JOHN DAVIDSON, OF LONDON, ENGLAND, ASSIGNOR OF ONE-HALF TO THE AUTOMATIC MEMORANDUM CLOCK COMPANY, LIMITED, OF SAME PLACE.

PROGRAM-CLOCK.

SPECIFICATION forming part of Letters Patent No. 595,767, dated December 21, 1897.

Application filed December 9, 1896. Serial No. 615,053. (No model.)

To all whom it may concern:

Be it known that I, JOHN DAVIDSON, watchmaker, a subject of the Queen of Great Britain, residing at 42 Holborn Viaduct, in the city of London, England, have invented a new and useful Improved Automatic Memorandum-Clock, of which the following is a specification.

This invention relates more particularly to

10 that type of automatic memorandum-clocks embraced in patent granted to me and numbered 466,712, A. D. 1891, in which the starting of an alarm is effected through the medium of tablets inserted in a drum revolved by an ordinary clock-movement.

In clocks constructed and operating according to the above-mentioned patent the drum during its revolution drops the previously-inserted tablets onto a platform, which is thereby operated to effect the starting of the alarm. Now my primary object is to dispense with the necessity of the tablets being so dropped by arranging that these may operate the alarm as they revolve with the drum.

25 As constructed according to my present invention, the clock may be arranged with its dial in either a vertical or horizontal plane, as desired, and I will describe one with a horizontal dial.

30 Secured in a case or frame of suitable construction is a clock-movement of any ordinary type, and to the spindle of this, which usually carries the hour-hand, is secured a drum divided into a prearranged number of radial pockets suitably marked. An index-finger forming the hour-hand is secured to or formed on the upper surface or edge of this drum and moved over an annular dial, while the usual minute-hand is arranged as

40 heretofore in clocks of ordinary construction. The outer ends of the radial pockets in the drum are open, and into the annular opening thus formed in the periphery of the drum projects one end of the operating lever or arm or the like, which, when turned or operated as

allow the latter to pass it, starts the alarm, which may be either an electric or mechanical one.

An alarm-clock constructed according to my invention is illustrated by the accompanying drawings, and by the aid of these I will now further describe the same and the manner in which it may be carried into practical effect.

Of the drawings, Figure 1 is a sectional elevation, and Fig. 2 a plan, of a clock having a horizontal dial combined with an ink-stand. Fig. 3 is a plan view with parts broken away to show the electrical connections.

In the frame *a*, which carries the ink-wells *b*, is secured a clock-movement *c* of any suitable construction, either by the aid of stays *d* or otherwise. On the spindle *e* of this movement is mounted a drum *f*, divided into a number of radial pockets suitably marked. This drum carries an index-finger *g*, forming the hour-hand of the clock and arranged to move over an annular dial *h*, while the minute-hand is arranged as in a clock of ordinary construction.

The outer ends of the pockets in the drum are open, so that an arm or other portion operating an alarm may project into the annular recesses so formed to such an extent that it will be operated as the drum revolves by a previously-inserted tablet, such as *k*, and an alarm sounded.

The alarm may be an electric or mechanical one, as desired; but as shown in the illustration it is electrical, the ends of the circuit being connected to the arm *l* and the contact *m*, so that when said arm *l* is turned against the pressure of a spring *n* by a tablet carried by the drum striking one end of it its opposite end will be forced against the contact *m* and so complete the circuit through the bell *o* and battery *p*.

The position of the switch or the like operating the alarm may be indicated on the dial or otherwise, so that when the alarm is started the required tablet may be withdrawn and examined, while the case *a* may be pro-

vided with a hinged bezel a' of suitable construction.

What I claim is—

5 A memorandum-clock comprising a rotary drum having radial pockets extending vertically through the same at or near its periphery, the said periphery being open laterally,

the contact extending into said open periphery and into the path of the tablets and the pointer and dial, substantially as described. 10

JOHN DAVIDSON.
